(57) CLAIM

The ornamental design for a sandal, as shown and described.

DESCRIPTION

The patent or application file contains at least one drawing executed in color. Copies of this patent or patent application publication with color drawing(s) will be provided by the Office upon request and payment of the necessary fee.

1. Sandal

1.1 : Perspective

1.2 : Front

1.3 : Back

1.4 : Right

1.5 : Left

1.6 : Top

1.7 : Bottom

The sandal comprises a sole and two transversal straps resembling chains; the strap that, in use, rests on the instep has a central part in the form of an anchor chain link; the reproductions of the design show a right sandal, the corresponding left sandal being the mirror image of the one shown in the reproductions; in the reproductions of the design the blurred elements in pink are not claimed.
